UNITED STATES PATENT OFFICE.

CHESTER PROUTY, OF RIDGWAY, PENNSYLVANIA.

PEAVY.

SPECIFICATION forming part of Letters Patent No. 627,528, dated June 27, 1899.

Application filed September 17, 1898. Serial No. 691,176. (No model.)

To all whom it may concern:

Be it known that I, CHESTER PROUTY, a citizen of the United States, residing at Ridgway, in the county of Elk and State of Pennsylvania, have invented certain new and useful Improvements in Peavies; and I do hereby declare the following to be a full, clear, and exact description of the invention, such as will enable others skilled in the art to which it applies to make and use the same.

My invention relates to improvements in peavies of that class which are distinguished from those devices disclosed in another application (Case A) filed by me September 13, 1898, and bearing Serial No. 690,877, owing to the fact that the pick and staff are driven or inserted in opposite directions into a double-socketed ferrule or band and one pick is received within a bore in the tapered tenon of said staff, thus making the implement relate to that class known as "driven-pick" peavies in contradistinction to the implements in which the pick is welded or united firmly to the ferrule or band. In implements of this class as heretofore constructed it has been customary to make the staff in a large heavy piece and the band or ferrule of thin metal, uniform in thickness, and of just sufficient size to stand the strain of the pick and cant-dog; but in the practical service of prior devices it is found that besides being heavy, cumbersome, and unwieldy in the hands of the operator the pick is frequently broken off at the point where it joins with the staff and ferrule, thus involving expense, delay, and annoyance to the user. I aim to minimize these objections by a new construction which increases the strength and durability at the juncture of the pick and staff at the handle and in which all the parts contribute to the end of preventing the pick from working loose under the shrinkage of the wooden staff during the drying of the staff in hot weather and other atmospheric changes. I also aim to reduce the size of the implement and to bring the butt of the pivoted hook in exceedingly compact relation to the staff and the ferrule, thus promoting the convenience of the operator in the manipulation of the implement; and a further object of the invention is to provide durable and efficient front and back

stops for the pivoted timber-hook which will obviate wear on the wooden handle.

The invention consists in the construction and arrangement of parts, which will be hereinafter described, and pointed out in the claims.

A preferred embodiment of the invention is represented by the accompanying drawings, forming a part of this specification, in which—

Figure 1 is a side elevation of a peavy embodying the present improvements. Fig. 2 is a longitudinal section of the device shown by Fig. 1. Fig. 3 is a transverse section on the line $x-x$ of Fig. 2. Fig. 4 is a detail view 65 of the ferrule or band removed from the staff. Fig. 5 is a detail view of the rolled sheet-steel blank invented by me for the manufacture of the ferrule or band shown by Fig. 4. Fig. 6 is a detail view of the rolled pick forming 70 one of the improvements embraced by the present invention. Fig. 7 is a detail sectional elevation of the staff. Fig. 8 is a sectional elevation of a modified construction of the peavy. Figs. 9 and 10 are views of rolled 75 metal and blanks contemplated by this invention, and Fig. 11 is a top plan view of a modified form of ferrule.

Like numerals of reference denote like and corresponding parts in each figure of the drawings.

The staff or handle 10 is of peculiar form to receive one end of the pick 11, and it is thrust into a ferrule or band 12 to provide an exceedingly strong joint between the several 85 elements to adapt the implement to withstand the strain at the point where the pick is most exposed or subjected to breakage in the practical service of the implement. This metallic ferrule or band 12 is one of the important features of my improved peavy, and while it may be cast of suitable metal, such as malleable iron, I prefer to roll it from sheet-steel to effect economy and expedition in the manufacture and produce a novel and simple 90 device adapted to strengthen the implement at the joint between the pick and staff and which serves conjunctively with the pick in preventing the latter from working loose under shrinkage due to atmospheric changes. 100 The rolled metal blank is represented by Fig. 5 and is designated by the numeral 14. It

is rolled in flat form and tapered from a line *m* near one edge toward the other edge, so that at the line *n* the metal is of less thickness or gage than at the line *m*, and at the line *o* it is thinner than at the lines *m n*, while the blank is tapered in an opposite direction from the line *m*, thus giving the blank a double taper. This blank is also provided at its thin edge with a series of lips or prongs 15, 10 giving to the blank a scalloped appearance; and it is furthermore provided at its side edges with the flanges 16, which are divided by the incisions or notches 17 from the edges of the blank beyond which the flanges 16 15 project. The blank having been rolled in the form described, it is prepared for use by shaping it to conico-cylindrical form by bending the blank around a suitable form and welding the beveled edges together, and then the 20 flanges 16 are bent to lie radially to the longitudinal axis of the ferrule. In the process of forming the ferrule or band a thickened shoulder 18 is produced in advance of the flanges to constitute a front stop for the pivoted hook, a flat metallic face 19 is formed 25 between the flanges to serve as a back stop for said cant-dog, and a transverse slot 20 is made in the ferrule between the flanges to accommodate the eye-formed end of the log-hook 30 21. The flanges 16 do not project or protrude from the face of the ferrule for any considerable distance; but, on the contrary, they are narrow, so as to occupy a compact relation to the ferrule, and by this construction of the 35 ferrule and by a notch or recess in the staff the hook has its heel arranged in compact relation to the ferrule and the staff, so that the implement can be used with greater convenience by the lumberman in rolling different-sized logs. 40 This cant-dog is formed at its heel with an eye 22, and it is arranged to fit between the flanges to pass through or work in the slot of the ferrule and to lie in or occupy the notch or recess of the staff. This cant-dog is connected 45 pivotally to the ferrule by a bolt 23, which passes through coincident openings in the flanges and the eye of the dog-heel, and this bolt receives a suitable nut. The front concave edge of the dog is formed adjacent 50 to the eye-formed heel with a stop-shoulder 24, adapted to abut against the front stop-face of the ferrule, and the rear edge of the cant-dog is arranged to bear against the back stop-face of the ferrule when the hook is thrown 55 backward, thus providing metallic bearing-faces for the dog at the limits of the forward-and-backward throw.

The staff 10 is a single piece of wood having one end turned and bored to adapt it for 60 union with the band or ferrule and the stem of the pick. To facilitate and cheapen the manufacture of the implement and render the staffs interchangeable with the socketed ferrules or bands, I chuck each staff in a turning machine or lathe and chuck and rim on one end of the staff a tapered tenon 26, and

after removing the staff from the machine or lathe a tapered socket 27 is bored into the tapered tenon of the staff.

The pick 11 is prepared from steel by rolling it to the proper contour, (shown by the drawings,) and this pick consists of the pick proper, 11, the shank or tang 28, and the shoulder 29. The pick has facets 30, which are inclined and disposed at angles to make 75 the pick present the tapered form square in cross-section. The tang 28 may be either round or angular in cross-section; but it is essential that it shall taper in a contrary direction to the taper of the pick. The reverse 80 tapers to the pick and the tang result in the formation of the circumferential shoulder 29, and this is increased by slight concavity or curvature of the tang, as at 31, adjacent to the shoulder, thus making the facets of the 85 pick more prominent and well defined.

By producing the tapered metal blank and subsequently bending it to shape around a form the ferrule or band is provided with a tapered staff-socket 32, and the metal of the 90 band is made much thicker and stronger near the lower end, such metal tapering or decreasing from its thickened end portion toward the large upper end of the socket portion of the ferrule or band. The socketed 95 lower portion of the band flares, as at 33, from the thickened part in an opposite direction from the staff-socket 32, and this flared part 33 of the ferrule-socket is adapted to receive the sloped intermediate part of the 100 pick, so that the shouldered square pick is caused to bind firmly against the socket or small end of the ferrule. The tenon of the 105 wooden staff terminates at the socket 32 of the ferrule at the end of the flared portion 33 and the shouldered part of the pick, and thus the pick is adapted to have metallic bearing against the ferrule, and its shank is wedged in the bored part of the staff. By 110 wedging the tang in the bored end of the staff and wedging the shouldered part of the pick against the end of the socket portion of the ferrule the parts are all intimately and solidly united together and prevent any tendency to work loose and the wooden staff is 115 prevented from shrinkage under atmospheric changes, thus obviating loosening of the pick. The joint is materially strengthened by increasing the thickness of the metal forming 120 the band at the point where the square shoulders of the pick meets the ferrule and the staff, and the tendency of the staff to separate from the ferrule is further counteracted by the clenched lips or prongs, which are provided at the thin upper edge of the ferrule 125 and are bent over and embedded in the wood at a line above the beginning of the taper in the staff-tenon. At a point intermediate of the length of said tapered tenon in the staff is provided a notch or recess coincident with 130 the slot in the ferrule or band, and it receives the heel of the pivoted cant-dog, so that the

latter may be pivoted close to the ferrule and the transverse diameter of the implement reduced within a narrow compass.

My improved construction enables the implement to be made smaller and lighter than the ordinary peavy of commerce, and at the same time the implement is strengthened because the band or ferrule is thickened at the point where the pick is exposed to the greatest strain and where the pick-tang and staff meet each other within the socketed band, thus adding stability to the implement at the place where the greatest strain is exerted thereon in the practical service of the tool.

15 The wooden staff is not liable to shrink in the socketed ferrule to such an extent as to loosen the socket by shrinkage of the wooden staff, which has a tendency to tighten the pick, because the lower end of the ferrule is closed 20 by the shouldered pick, and the wood is thus partly housed and protected, and the joint between the ferrule and the pick obviates the formation of an abrupt enlarged shoulder at the reduced end of the ferrule. The hook 25 lies in a compact relation to the ferrule and staff, so as to decrease the diameter of the implement, and the heel of said dog is housed in the ferrule and the staff instead of projecting beyond the staff, as is ordinarily the 30 case.

Part of my improvements are applicable to cant-hooks. While I prefer to make the ferrule long enough to accommodate both the pick and the cant-dog, I do not strictly confine myself to this particular arrangement, because the ferrule may be divided, as shown 35 by Fig. 8. The band 36 to fit over the end of the staff and receive the pick is separate from the clip 37, which is secured around the staff 40 and receives the heel and pivot-bolt of the cant-dog. This clip is rolled in a single piece, with the thickened edges 38 adapted to be bent to form the flanges, and these flanges have bolt-holes to receive the bolt by which 45 the clip may be clamped and the dog pivoted. The clip has a series of lips 39, adapted to be bent into the staff and serve to hold the clip firmly in place on the staff. The metal to form the clips may be rolled in a sheet or 50 length, as shown by Fig. 10, which is to be sheared transversely and then fashioned and bent to produce the clip, and this construction enables the clips to be manufactured rapidly and economically.

55 I am aware that changes and alterations in the form and proportion of parts and in the details of construction of the devices herein shown and described as the preferred embodiment of my invention may be made by a 60 skilled mechanic without departing from the

spirit or sacrificing the advantages thereof, and I therefore reserve the right to make such modifications as fairly fall within the scope of my invention.

I do not herein make any claim to novel features of the embodiment of my invention herein illustrated which are also incident to the invention illustrated in my aforesaid earlier application, Serial No. 690,877, preferring to present such claims in that case. 65 70

Having thus fully described my invention, what I claim as new, and desire to secure by Letters Patent, is—

1. In a peavy, the rolled and doubled ferrule or band having the tapered staff-socket 75 which flares toward one end of the ferrule and has walls which gradually decrease in thickness longitudinally in opposite directions from an intermediate point to provide the thickest part of the metal around the staff at 80 the narrowest portion of the socket, combined with a tapered and socketed staff fitted in the ferrule or band, and a shouldered pick with a tang inserted in the ferrule and the staff, substantially as described. 85

2. A peavy comprising a tapered conico-cylindrical ferrule or band having the two oppositely-extending flared socket portions the adjacent ends of which are at the thickest metallic section of the ferrule, a pick provided 90 with the tapered tang and with the shoulder which is wedged in the flared portion of the socketed ferrule, and a tapered and socketed staff wedged in the ferrule and receiving the tang of the pick, substantially as described. 95

3. A peavy comprising a tapered conico-cylindrical ferrule having the clenchable prongs at its upper edge, the flared socketed portion adjacent to the thickest metallic length thereof, a slot between the pivotal flanges, and the front and back stops on opposite sides of the slot; a staff having the tapered socketed tenon wedged into the ferrule and provided with a notch which is coincident with the slot in the ferrule; a pick having the 100 tapered tang and the shoulder between the tang and pick and wedged into the flared thickened end of the ferrule for the tang to enter the staff-socket, and a shouldered cant-dog having its heel fitted in the ferrule-slot 110 and the staff-recess and pivoted to the flanges for its front shouldered edge and its back edges to bear against the stop-faces of the ferrule, substantially as described. 105

In testimony whereof I affix my signature 115 in presence of two witnesses.

CHESTER PROUTY.
